(57) **CLAIM**

The ornamental design for a drawer organizer, as shown and described.

DESCRIPTION

FIG. 1 is a perspective view of a drawer organizer showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a front, bottom, and left side perspective view thereof;

FIG. 9 is a front, bottom, and right side perspective view thereof;

FIG. 10 is a perspective view of second configuration of a drawer organizer, shown in an opened condition;

FIG. 11 is a perspective view of third configuration of a drawer organizer, shown in an opened condition; and,

FIG. 12 is a perspective view of fourth configuration of a drawer organizer, shown in an opened condition.

The broken lines in the drawings depict portions of the drawer organizer that form no part of the claimed design.

1 Claim, 12 Drawing Sheets
